US00D875950S

(12) **United States Design Patent** (10) **Patent No.:** **US D875,950 S**
(45) **Date of Patent:** **** Feb. 18, 2020**

(54) **COT FASTENER**

(71) Applicant: **Stryker Corporation**, Kalamazoo, MI (US)

(72) Inventors: **Brandon David Naber**, Portage, MI (US); **Kurosh Nahavandi**, Portage, MI (US); **Nathan Wray Matheny**, Portage, MI (US); **Michael T. Brubaker**, Portage, MI (US); **Charles Louis Crouch**, Plainwell, MI (US); **Jason James Wroblewski**, Kalamazoo, MI (US); **Clifford Edwin Lambarth**, Portage, MI (US)

(73) Assignee: **Stryker Corporation**, Kalamazoo, MI (US)

(**) Term: **15 Years**

(21) Appl. No.: **29/668,739**

(22) Filed: **Nov. 1, 2018**

Related U.S. Application Data

(63) Continuation of application No. 29/613,059, filed on Aug. 7, 2017, now Pat. No. Des. 833,623, which is a continuation of application No. 29/536,593, filed on Aug. 18, 2015, now Pat. No. Des. 794,205, application No. 29/668,739, which is a continuation of application No. 16/025,526, filed on Jul. 2, 2018, which is a continuation of application No. 15/290,004, filed on Oct. 11, 2016, now Pat. No. 10,058,464.
